UNITED STATES PATENT OFFICE.

F. DU PONT MARSTON, OF PHILADELPHIA, PENNSYLVANIA.

ELECTRICAL TELEPHONE.

SPECIFICATION forming part of Letters Patent No. 380,905, dated April 10, 1888.

Application filed April 15, 1887. Serial No. 234,908. (No model.)

To all whom it may concern:

Be it known that I, F. DU PONT MARSTON, a citizen of the United States, residing in the city and county of Philadelphia, State of Pennsylvania, have invented a new and useful Improvement in Electrical Telephones, of which the following specification, taken in connection with the accompanying drawings, is a full, clear, and exact description.

10 This invention is an improvement upon a telephone patented to me October 27, 1885, No. 329,327; and it consists in certain details, hereinafter enumerated, and particularly pointed out in the claims.

15 Figure 1 is a vertical section of my instrument through the electrodes and sound conducting tube. Fig. 2 is a perspective view of the diaphragm with its attached conductor. Fig. 3 is a side elevation of the instrument, 20 showing all its connections. Fig. 4 is a cross-section of a modified form of the gravity-electrode.

Similar letters of reference indicate corresponding parts in the several figures.

25 In my patent, No. 329,327, above referred to I have shown and described a contact-telephone with a horizontal diaphragm of glass carrying one electrode, the other electrode being sustained by gravity upon the first.

30 In the present application I have substituted for the glass diaphragm a diaphragm of carbon having a metal or wire conductor extending entirely around it and leading to one pole of the battery, the other electrode being a loose 35 carbon rod or ball resting by gravity on the diaphragm and connected, as is usual, to the second pole of the battery through the primary of an induction-coil or in any other well-known manner.

40 Referring, now, to the drawings, A represents the sustaining-base for carrying the working parts of the instrument.

J is a tube or passage for conducting the sound-waves to a point beneath the center of 45 the diaphragm B.

Upon the diaphragm, which constitutes one electrode, rests the other electrode, F, consisting of a rod or ball of carbon free to slide into and out of a guide-tube, G, which latter is 50 supported by flat spring or springs D, attached

to a rim, E, upon which the diaphragm rests.

It will be observed that the diaphragm B has a metal band or wire, G', extending entirely around it, so that sure electrical contact is had at all points of its circumference.

55

In the drawings I have shown the conductor G' attached to the diaphragm by winding the wire in a groove in the edge thereof; but I prefer to attach these parts by electroplating, or to attach a metal band to the diaphragm in 60 a similar manner and then connect the conductor directly to it by soldering or otherwise, this affording a sure and absolute electrical contact between the diaphragm and conduct- 65 ing-wire.

The movable electrode F is usually electroplated on its sides and upper end and adapted to fit snugly but without unnecessary friction into the guide-tube G, of hard rubber or other smooth material, so as to exclude dirt from its 70 contact. I also provide a cap or plug, H, for closing the upper end of the tube G and ex- 75 cluding dirt and similar insulating material from the tube G. This tube G rests directly on the diaphragm in such manner that dirt from below.

In place of the solid electrode F (shown in Fig. 1) I may use a hollow electrode of car- 80 bon or other material, with means for chang- ing its weight, as shown in Fig. 4, in which N is a cavity in the electrode, and o mercury or any weight, which may be increased or de- creased at pleasure. I may also and some- 85 times do use a platinum point or tip on the gravity-electrode, as shown at R, Fig. 4, and such tips may be used with the electrode shown in Fig. 1, if desired.

L represents the door of the transmitter-box, and M a flat spring located in the rear of the 90 part A to cause said part to be held firmly against the door when closed.

K is a cushion of rubber, paper, felt, or analogous material for supporting the dia- 95 phragm, as is usual in the art. This cushion may be omitted, if desired.

The mode of operation is analogous to that of all well-known contact-telephones, and particularly those using gravity-electrodes, and need not be described.

100

Having thus described my invention, what I claim as new, and desire to secure by Letters Patent, is—

1. A telephone with two carbon electrodes, one only of which has a peripheral connection with a transmitting electrical generator, the other being held loosely in a guide, substantially as described.
2. A telephone having a carbon diaphragm with peripheral contact, as described, a loose gravitating electrode of smaller dimensions than the diaphragm upon which it rests, and

a sound-conveying tube located beneath the diaphragm, substantially as described.

3. In a telephone, a horizontal carbon diaphragm having a peripheral connection for one conductor, a gravitating electrode being sustained in a dust-tight guide-tube, substantially as described. 15
